OTHER PUBLICATIONSPEtec 3-Stage Electric Knife Sharpener by Wusthof at Swiss Knife Shop. Downloaded from <http://www.swissknifeshop.com/precision-edge-technology-3-stage-knife-sharpener-by-w...> Dec. 11, 2012.*Primary Examiner — Philip S Hyder*Assistant Examiner* — Roselynne Cody(74) *Attorney, Agent, or Firm* — Novak Druce Connolly Bove + Quigg LLP**CLAIM**

The ornamental design for a three stage knife sharpener, as shown and described.

DESCRIPTION

FIG. 1 is a perspective view of a three stage knife sharpener showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate portions of the three stage knife sharpener that form no part of the claim.
